UNITED STATES PATENT OFFICE

CHARLES HORACE RUSSELL COLLINS, OF BONDI, NEAR SYDNEY, NEW SOUTH WALES,
AUSTRALIA

LASTING APPARATUS

Application filed October 12, 1928, Serial No. 312,136, and in Australia October 28, 1927.

According to this invention, boots and shoe uppers are "pulled over" and "lasted" in a machine in which the upper is drafted and its skirt infolded, pleated, and pressed down on the insole by pneumatic means and held in close contact therewith by those means until attachment between the sole and the upper skirt has been established by an adhesive which is applied to the surfaces before 5 the parts are set up in the pneumatic machine. The invention is thus broadly distinguishable from the prior art in which the drafting, pulling over, and lasting are performed either manually or by mechanical 10 devices co-operating with manual manipulation.

Apparatus embodying the invention will be more fully described with reference to the accompanying drawings, in which:

20 Fig. 1 is a vertical sectional elevation of the machine; and

Fig. 2 is a fragmentary sectional view on enlarged scale illustrating part of the operation of the machine.

25 10 is one of the end frames of the machine, and 11 a yoke which is pivotally mounted thereon at 12 on a bracket 13 and extends rearwardly over the frame 10; the vertical end of the yoke 11 is fitted with a cam claw lever 14 which is fulcrumed on a pin 15 and is engageable with a staple pin 16 fixed on a lug 17 on the frame 10 to lock down the yoke.

18 and 19 are adjusting screws tapped through the yoke; they carry a follower block 20 which is shaped to set within a margin ring 21 which is secured down to the rim of the open top jack mould 22 by means of bolts or studs 23. The jack mould 22 may 30 be fixed in the frame 10 or built integral with it. It is shaped to contain a lasted upper within a diaphragm or liner 24 of shaped flexible rubber. The lip portion 25 of this diaphragm is secured to the cover ring 21 which is fixed by bolts 23 to the rim portion 35 of the jack mould 22, and its depth is substantially greater than the depth of the last in order to leave a deep margin or space above and about the edges of the sole of the shoe, this space being necessary to allow the dia-

phragm to fold in over the shoe sole as seen in Fig. 2. The follower block 20 is shaped on its under side 20A to correspond with the contour of the shoe insole on the wood or metal last 26 and to offer clearance for the infolding of the marginal part of the dia- 55 phragm. Air holes may be provided to allow the air to be displaced from the said margin or space above the sole when the diaphragm is placed under pressure. The marginal part of the face of the diaphragm which down- 60 folds on the skirt of the upper is appropriately corrugated in order to lay the pleating of the upper skirt symmetrically, particularly around the toe and heel. The yoke 11 is locked down by means of the cam lock 65 lever 14. The margin of the insole and the inner face of the upper skirt are served with rubber solution or paste or other suitable agglutinant before or after the shoe on the last is set in the jack mould. The lower part 70 of the jack mould 22 has a cylinder 40 fitted to it. A plunger works through a stuffing box 28 in this cylinder, and the space between the head of the piston 27 and the diaphragm 24 contains water or other fluid which will 75 not injure the rubber. In practice water is preferably used. The bottom end of the plunger 27 is articulated through an extensible link 29 with a rock lever 30 which is fulcrumed on the back part of the frame 10. 80 This rock lever 30 is actuated by an offset roller pin 33 on a pedal lever 31 which is fulcrumed on the frame 10 at 32. 35 is an arcuate bar pivoted to the frame at 35* and having a stop 34 at the upper end engageable 85 with the lever 31; the curve of this bar is swept from the centre of the pedal lever fulcrum 32; the face of it slides over the face 36 on the back of a pedal 37; the pedal is fulcrumed on the pedal lever 31 at 38. The 90 disposition of the centres is such that when the pedal 37 is tipped backward the arcuate bar 35 is pinched between the pedal face 36 and the stop 33* and the pedal lever is thus locked; the plunger 27 is thus held in raised 95 position in the cylinder maintaining pressure on the diaphragm during the setting period in which the skirt upper becomes fixed to the insole. When the pedal 37 is tilted forward- 100 ly and permitted to rise by easing foot pres-

sure on it, its grip of the bar 35 is released and the lever 31 may then rise and the plunger 27 descend to release the pressure on the diaphragm.

- 5 When the pedal lever 31 is depressed, upward thrust is applied to the plunger 27. The water or other fluid below the diaphragm being thus placed under compression presses upward and inward over the whole area of the diaphragm. The diaphragm, being elastic, is thus caused to stretch. In stretching, it draws or "drafts" the upper tightly over the last so that a good shaping is assured and the fullness is brought down to the skirt. The pressure acting on the diaphragm 24 also 10 folds it inward (see Fig. 2) over the insole forcing down the upstanding skirt portion of the upper on the insole. In this "pulling over" of the upper, the diaphragm operates to pleat the skirt symmetrically down over the insole on the bottom of the last so that the crimps are flattened as if they had been hammered down. A period of rest of a few 15 seconds to allow for the setting of the agglutinant under pressure is allowed; then the pressure is released by tilting the pedal to allow the lever 31 to rise and the plunger 27 to descend. The latch 14 is then released and the yoke 11 thereby lifted out the fol- 20 lower block 20. If so desired, the skirt of the upper may be tacked down to the insole after the follower has been lifted. The last, carrying the upper and the insole, may then be lifted out of the mould jack.
- 25 In operating the machine, the upper 50 is stretched over the last 26 with its skirt portions upstanding as shown in Fig. 1, the thus covered last is set in the jack mould, and the insole is set over the sole part of the last. The marginal portions of the insole and the upper skirt are served with a quick drying rubber solution or an adhesive paste. The follower block 20 is now set down to bear 30 on the insole. The marginal part of the insole on which the skirt of the upper is to be set is not covered by the block 20. Correct adjustment of the set of the follower block on the insole is obtained by means of the screw 35 studs 18-19.
- 40 If, however, it is required to attach the wearing sole to the shoe by rubber gum or like adhesive, the last with the insole and upper upon it is retained on the jack mould and a surfacing of adhesive is applied over 45 the insole and the "pulled over" skirt of the upper, and a sole piece is set in position over them after first spreading agglutinant upon it. The follower 20 is then brought down over it, the yoke relocked, and pressure then 50 re-applied under the diaphragm, with the result that the wear sole is pressed hard down upon the insole and the pleated-in skirt, the agglutinating material is spread between the wear sole and the insole and the lasted-in 55 skirt of the upper; and a clean strong attach-

ment is obtained. The pressure is maintained as before until the agglutinant is sufficiently set. The follower 20 may be steam heated or electrically heated to effect vulcanization of the wear sole piece onto the boot body.

70 What I claim as my invention and desire to secure by Letters Patent is:—

A shoe lasting machine comprising an open top jack mould, an open top inflatable diaphragm fitting closely within said mould with its edges fixed to the rim of the mould, a sole shape follower block adapted to pass into the open top of the diaphragm and to bear upon the sole of a shoe contained therein, means for introducing fluid into the interstitial space between the jack mould and the diaphragm, said means including a cylinder, a plunger operative in said cylinder to apply pressure upon said fluid to distend the diaphragm in the mould, a pedal lever operatively connected to said plunger, and means for locking said lever in position to maintain pressure on the diaphragm.

75 80 85 90 95 100 105 110 115 120 125 130

In testimony whereof I affix my signature.

CHARLES HORACE RUSSELL COLLINS.
